UNITED STATES PATENT OFFICE

FRANK J. SCHLEICHER, OF ST. LOUIS, MISSOURI

DESIGN FOR A BOX

Application filed May 13, 1931. Serial No. 39,840. Term of patent 7 years.

To all whom it may concern:

Be it known that I, FRANK J. SCHLEICHER, a citizen of the United States, residing at the city of St. Louis and State of Missouri, have invented a new, original, and ornamental Design for Box, of which the following is a specification, reference being had to the accompanying drawing, forming part thereof.

The drawing is a perspective view showing my new design for a box.

The drawing has been shaded to represent contrasting colors in the design. The pencil and tassel element of the design is secured to the top of the box.

I claim:

The ornamental design for a box, substantially as shown and described.

FRANK J. SCHLEICHER.
